UNITED STATES PATENT OFFICE.

GEORGE L. MATHER, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

DESIGN FOR A TIRE.

Application filed August 30, 1923. Serial No. 7,122. Term of patent 14 years.

To all whom it may concern:

Be it known that I, GEORGE L. MATHER, a citizen of the United States, residing at Milwaukee, in the county of Milwaukee and State of Wisconsin, have invented a new, original, and ornamental Design for a Tire, of which the following is a specification, reference being had to the accompanying drawing, which forms a part thereof and in which—

I claim:

The ornamental design for a tire substantially as shown.

GEORGE L. MATHER.
